Primary Examiner — Kelley Donnelly(74) *Attorney, Agent, or Firm* — Timothy X. Gibson, Esq.;
Gibson & Dernier LLP**CLAIM**

The ornamental design for a coffee service tray, as shown and described.

DESCRIPTION

FIG. 1 is a front perspective view of a first embodiment of the coffee service tray of the present invention;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a front perspective view of a second embodiment of the coffee service tray of the present invention.

The broken line showing in FIGS. 1 and 8 in the drawings are for the purpose of illustrating the environment of the design only and form no part of the claimed design.
